UNITED STATES PATENT OFFICE.

RALPH V. SAGE, OF WESTMONT BOROUGH, PENNSYLVANIA.

CAR CONSTRUCTION AND ARRANGEMENT OF DROP-DOORS AND OPERATING MECHANISM.

1,074,981.

Specification of Letters Patent.

Patented Oct. 7, 1913.

Application filed June 20, 1913. Serial No. 774,852.

To all whom it may concern:

Be it known that I, RALPH V. SAGE, a citizen of the United States, residing in the borough of Westmont, in the county of Cambria and State of Pennsylvania, have invented 5 certain new and useful Improvements in Car Construction and Arrangement of Drop-Doors and Operating Mechanism; and I do hereby declare the following to be a full, 10 clear, and exact description of the invention, such as will enable others skilled in the art to which it appertains to make and use the same.

My invention relates to railway cars and 15 more particularly to the manner of constructing that part of the framing and sides coöperating with the hinged drop doors and their operating mechanism.

One of the objects of my invention is to 20 provide a simple, strong and economical construction especially adapted for that class of freight cars known as drop bottom gondolas in which a plurality of drop doors are located between the cross bearers longitudinally hinged to or near the center sills, and 25 which form the car flooring to a great extent when they are closed.

Another object of my invention is to form 30 the cross bearers with upwardly bent outer ends which may be attached directly to the side stakes or to the car side on which ends is secured a longitudinally extending laterally inclined shedding plate, either as a 35 separate piece, or a portion of the side sheet.

A further object of my invention resides 40 in mounting the door operating shaft in journal bearings secured to the downwardly extending lower ends of the car stakes, so that the door operating mechanism can be easily accessible for mounting, demounting 45 and inspection, but at the same time in a position where it will be protected by the body of the car.

Another object of my invention is the 45 bracing of the ends of the cross bearers to the car sides or stakes to form a more rigid construction at this point.

My invention also consists in the novel 50 constructions, arrangement and combination of parts, substantially as hereinafter described and pointed out in the appended claims.

Having given a general description of my invention, I will now, in order to make it

more clear, refer to the accompanying one 55 sheet of drawings forming part of this specification and in which:—

Figure 1 is a vertical transverse sectional elevation of a portion of a car taken on the line I—I of Fig. 2, looking in the direction 60 of the arrows, showing the upwardly inclined end of a rolled channel cross bearer attached directly to the side stake of the car, and the door operating shaft bearing secured to the lower end of the side stake below the 65 said cross bearer. Fig. 2 is a side elevation of Fig. 1. Fig. 3 is a detail transverse sectional elevation of the lower outer portion of a car taken on the same line as Fig. 1, but of a slightly modified construction in 70 which the cross bearer is of pressed metal having a vertical web and flanged edges formed integral therewith, while the lower end of the side sheet of the car is bent inwardly to correspond to the upwardly inclined end portion of the cross bearer and 75 attached to its upper flanged edge; the side stake of the car extending below the cross bearers a greater distance than in Figs. 1 and 2, and a flanged brace member riveted to 80 the lower end of the stake and to the bottom flange of the cross bearer, with the journal bearing for the door operating shaft mounted on the car stake between the ends of the cross bearer and the brace. Fig. 4 is a detail side elevation of another modification 85 in which the cross bearer is an I-beam and the side stake a pressed metal shape of V form.

Referring now to the numerals of reference on the drawings:—1 indicates the center sills of the car which may be rolled channels as shown, spaced apart by means of flanged shallow box-shaped members 2 and 3, and disposed with their webs vertical and 95 back to back, their flanges extending horizontally outward toward the sides of the car; or, the center sills may be of any other desired shape or conformation. A cover plate 4 is laid over and riveted to the top 100 flanges of the center sills 1 and to the top flanges of the box-shaped members 2 and 3 and serves as the central floor-strip of the car.

5 indicates the bolsters of the car, shown 105 as open boxes of trapezoidal shape, but which may be of any other construction. The cross bearers are spaced at suitable dis-

tances apart between the bolsters and have their inner ends attached to the center sills 1 in any approved manner and extend outwardly therefrom to the sides of the car, 5 their outer ends being bent upwardly as indicated at 7 and secured to the side stakes 8 of the car at an intermediate part thereof.

The side plate girder of the car is constructed with a vertical web portion 9, an 10 upper flange 22, as shown in Fig. 1, and a lower inclined portion 10, preferably formed integral with the web as shown, although these may be made separately and riveted together, if desired.

15 As shown in Figs. 1 and 2, the side stakes 8 are attached to the vertical web portion 9 of the girder side of the car and extend below the same, to which are riveted the bent-up ends 7 of the cross bearers 6 and on 20 said stakes, below the ends of the cross bearers, are secured journal bearings 11 for the door operating shaft 12, which shaft operates and supports the forward swinging end of the door 13. In cases where the 25 shaft extends to the end of the car, it passes through an enlarged hole in the bolster as indicated by the outer circle around same in Fig. 1. The forward swinging end of the door closes against the horizontal inner edge 14 which extends from the inclined lower portion 30 10 of the girder side of the car. It will be noted that the inclined lower portion 10 of the girder side of the car forms a shedding plate by means of which granular or 35 similar materials may be more readily discharged through the door openings in the bottom of the car, and as this shedding portion 10 is riveted directly to the top flange of the bent end 7 of the cross bearer 6, the 40 inclination may be varied by bending the end of the cross bearer to a greater or less degree. This plate girder side construction obviates the necessity of heavy side sills at, or below, the floor level of the car and 45 allows easy access to the parts supported below the car body.

A door operating shaft 12 extends longitudinally of the car and on each side thereof and is entirely supported by the journal 50 bearings 11 attached to the lower ends of the car stakes. As illustrated, only one shaft is shown, but it will be understood that the other side of the car is constructed similarly with suitable door operating mechanism 55 15 mounted thereon or connected therewith to the car door. Any desired mechanism may be used, but I prefer to use that disclosed by me in my co-pending application for improvements in dump-cars, filed October 3rd, 1912, Serial Number 60 723,665, but as the details of the door latches, etc., form no part of my present invention, a description of same is not given herein.

In Fig. 3 I have shown a modified form 65 of a cross bearer 16 made of pressed metal

with bent-up outer end portion 17. This cross bearer has a vertical web with integral flanges around the outer edges thereof. In this construction the car stake 8 extends downwardly below the car side a greater distance than that shown in Figs. 1 and 2, and I provide a pressed metal brace 18 having a vertical web with integral flanges extending entirely around the outer edges thereof, one end of which brace is attached to the lower end of the stake, from which point it inclines upwardly and its outer end is secured to the lower flange of the cross bearer 16. A triangular-shaped space is left between the bent-up end 17 of the cross bearer 16, the brace 18 and the projecting end of the side stake 8, in which space the journal bearings 11 are attached to the car stake and the door operating shaft 12 extends therethrough, as shown.

70 In Fig. 4 I have illustrated another modification in which an I-bar 19 is used for the cross bearer, and a pressed metal side stake 20 is used instead of the angle bar 8. This I-bar 19 and side stake 20 may be connected 75 together by means of angle brackets 21, or in any other approved manner.

80 While I have shown and described my invention in considerable detail, I do not wish to be limited to the exact construction specified, but may use such substitutions, modifications or equivalents thereof as are embraced within the scope of my invention, or 85 as pointed out in the claims.

90 Having thus described my invention, what I claim and desire to secure by Letters Patent is:—

1. In a railway car of the class described, a plate girder side the lower portion of which is downwardly and inwardly inclined, a plurality of cross bearers extending transversely of the car, the outer ends of which are upwardly inclined and secured to the inclined portion of the plate girder aforesaid, a plurality of stakes attached to 105 the car side and extending below the ends of the cross bearers, and a plurality of journal bearings mounted on the lower portions of said stakes below said inclines and adapted to 110 revolvably support an operating shaft.

115 2. In a railway car of the class described, a plate girder side the lower portion of which is downwardly and inwardly inclined and provided with a horizontal marginal edge, the inclined portion being adapted to 120 form a shedding plate and the edge a closure for the end of the swinging car-door, a plurality of cross bearers extending transversely of the underframing, the outer ends of which are upwardly inclined and secured 125 to the inclined portion of the plate side, a plurality of stakes secured to the car side and extending below the ends of the cross bearers, a plurality of journal bearings secured to the lower portions of the said 130

stakes, a door operating shaft mounted in said bearings extending longitudinally of the said car, and means actuated by said shaft for opening and closing the car doors.

5 3. In a car of the class described, a plurality of cross bearers, each comprising a flanged member extending transversely of the car underframing and having an upwardly inclined end portion secured to the

10 car side, a plurality of stakes attached to the car side and extending below the outer end of said cross bearers, and a brace extending from the lower end of each of said stakes to the intermediate portion of the corresponding cross bearer.

15 4. In a railway car of the class described, a center sill, plate girder sides, a plurality of doors hinged to the center sill, the lower portion of said plate girder side being

20 downwardly inclined and having a marginal edge portion adapted to contact with and form a closure for the ends of said doors, a plurality of side stakes secured to the outer side of the plate girder and extending

25 below the ends of the said cross bearers, a plurality of journal bearings mounted on the lower portions of said stakes, a door operating shaft mounted in said bearings and

means actuated by said shaft for opening and closing the doors.

5. In a railway car of the class described, the combination with the center sills, the side plate girders and drop doors hinged to the sills thereof, of a plurality of cross bearers extending from said sills to and attached to the plate girder sides, the outer ends of the said cross bearers being upwardly inclined, the lower portion of said plate girder being correspondingly inclined and secured to the inclined ends of the said

30 cross bearers, each of said cross bearers being provided with a floor strip extending lengthwise thereon and projecting over the edges of the same, stakes secured to and projecting below the car sides, a plurality of journal bearings secured to the lower ends of the said stakes, a door operating shaft mounted in said bearings, and means actuated by said shaft adapted to operate, open,

35 close and lock said doors.

40 In testimony whereof I hereto affix my signature in the presence of two witnesses.

RALPH V. SAGE.
